UNITED STATES PATENT OFFICE.

SYDNEY I. PRESCOTT, OF NEW YORK, N. Y., ASSIGNOR TO THE AMERICAN TOBACCO COMPANY, OF NEW YORK, N. Y., A CORPORATION OF NEW JERSEY.

PAPER-STRIP CONTROLLING AND PRINTING MECHANISM FOR CIGARETTE-MACHINES.

Specification of Letters Patent. Patented March 24, 1908.

No. 882,651.

Application filed May 14, 1906. Serial No. 316,687.

To all whom it may concern:

Be it known that I, SYDNEY I. PRESCOTT, a citizen of the United States, residing at New York, county of Kings, and State of New York, have invented certain new and useful Improvements in Paper-Strip Controlling and Printing Mechanism for Cigarette-Machines, fully described and represented in the following specification, and the accompanying drawings, forming a part of the same.

This invention relates to certain improvements in tube forming mechanisms of the kind employed in forming a thin continuous paper strip into a tube, such mechanisms being used in connection with cigarette machines. In such mechanisms, the paper strip is continuously drawn by the tube forming means from a suitable source of supply, such, for instance, as a reel. The paper employed, however, is very thin and it is difficult to maintain the exact amount of tension on it which is necessary to enable the tube forming means to perform their function with that accuracy required for the formation of perfect tubes.

The present invention has for its object to produce a mechanism for use in connection with devices for making a continuous tube, said mechanism operating to relieve the strains on the continuous paper strip and at the same time maintain a proper tension on the strip, so that the tube forming devices may operate with accuracy.

A further object of the invention is to produce a mechanism for use in connection with tube forming devices of the character referred to which shall relieve the strain and maintain the proper tension on the continuous paper strip and which may, at the same time, be employed for effecting other functions such as printing and bronzing.

Referring to the drawings—Figure 1 represents a plan view of a forming mechanism embodying the invention. Fig. 2 is a side elevation of the construction illustrated in Fig. 1. Fig. 3 is a section on the line 3—3 of Fig. 2. Fig. 4 is a section on the line 4—4 of Fig. 2. Fig. 5 is an elevation of the gearing which may be employed. Fig. 6 is a section on the line 6 of Fig. 1.

Continuous tube forming mechanisms of the character to which this invention is particularly applicable are used for the purpose of making tubes for cigarette machines, and

it is customary to apply distinguishing marks, such as trade marks or trade-names, to the paper strip prior to the time it is formed into a tube. The strain relieving and tensioning mechanism which forms the subject of this invention will, in the best constructions, be of such a character that it may be employed for the purpose of relieving the strain and maintaining the tension on the strip, and also for the purpose of applying the distinguishing marks referred to.

Machines embodying the invention will include devices for forming the paper strip into a tube. While these devices may be varied in construction, as illustrated, they include a mandrel indicated at 1 with which coöperates a pair of suitably driven crimping wheels 2, 3, the wheel 3 being, as is usual in such constructions, journaled in an opening in the mandrel. A tubular guide, indicated at 4, may be employed in connection with this mandrel to form the strip up around it, and there may also be employed suitable edge bending devices which are indicated at 6, 7. The tube forming devices, whatever be their construction, will operate to continuously draw a strip of paper from a suitable source of supply, as, for instance, a reel, indicated at 8. In the particular construction illustrated, the strip of paper marked 9, is first led between a pair of printing and impression rolls 10 and 11, these rolls being mounted on shafts 12, 13. The strip may be guided to these rolls by a roll 14, mounted on a shaft 15. The ink for the printing roll may be supplied from a fountain, as 16, this fountain having the usual inking roll 17. This roll 17 may be mounted on a shaft 18 which (see Fig. 5) is provided with a ratchet wheel 19, this wheel being driven by a pawl 20, as is usual in such constructions. The ink may be taken from the roll 17 by a ductor roll 21 eccentrically mounted on the shaft 22, this shaft carrying on its opposite end the pawl 20 before referred to which is also eccentrically mounted on the shaft. This ductor roll transfers the ink from the roll 17 to a set of distributing rolls 23, 24, 25, 26, the roll 26 being arranged to contact with the printing surface indicated at 27 (see Fig. 1) on the roll 10. The roll 23 is mounted on a shaft 28 which is positively driven and the other rolls are mounted on studs and driven by friction from the roll 23. The roll 10 is or may be provided with the

usual bearer flanges 29 to regulate the force of the impression on the paper strip. In order to facilitate threading the paper between the printing rolls, either the printing 5 or impression roll may be made movable. In the construction illustrated, the shaft 12 (see Figs. 1 and 6) is mounted in a bearing 30 formed in a slide plate 31, this plate having an upturned end, as indicated at 32. 10 Through this upturned end may work a clamp screw 33, this screw being tapped in a block 34 between which and the frame of the bed the slide 31 moves. This block 34 may be held in position in any suitable manner, as, 15 for instance, by screws 35. Distance screws 36 may be tapped through the upturned part 32 of the plate 31 and bear against the end of the plate 34, these screws making it possible, after the plate 31 has been moved, for the 20 purpose of threading the paper strip through the mechanism, to bring the printing roll back into exact adjustment it formerly occupied.

After passing between the printing rolls, 25 the paper is subjected to the operation of a strain relieving mechanism which may be variously constructed, but which will include a traveling surface or surfaces which run somewhat faster than the speed of the paper 30 strip. In the best constructions, furthermore, this traveling surface or surfaces may be utilized for applying bronze to the freshly printed strip. In the particular construction illustrated, the strain relieving mechanism 35 includes a set of bronzing wheels 37, 38 and 39, these wheels being mounted on positively driven shafts 40, 41 and 42. Co-operating with these bronzing wheels are the usual impression wheels 43, 44, 45, these 40 wheels being mounted on a positively driven shaft 46, 47, 48. The wheel 37 is a bronze applying wheel and is provided with an applying surface or pad taking bronze from a pick-up wheel 50 mounted on a positively driven 45 shaft 51, this wheel and the wheels 37, 38 and 39 running in a bronze box 52.

The construction is such that the printing 50 wheels run at the speed of the strip and the bronzing wheels run at a speed somewhat in excess of the speed of the strip, so that they exercise a kind of drawing or combing action on the strip, thus relieving the strain set up by the drawing action of the tube forming devices. The speed should, however, 55 be so calculated as to maintain that tension on the strip which is necessary for the accurate operation of the forming devices.

In the particular construction illustrated, the power for driving the various shafts 60 referred to is derived from a driving shaft 53 which may be one of the way-shafts of the machine and driven in any suitable manner. This shaft is provided with a spiral gear 54 which meshes with a similar gear 55 65 on a stud 56. This spiral gear carries a

gear which is located directly behind it, this gear meshing with a gear 57 on the shaft 42 before referred to which is the shaft on which the bronzing wheel 39 is mounted. It may be remarked that the wheel 39 as 70 well as the wheel 38 are brushing wheels which dust off the excess of bronze applied by the wheel 37 and are provided with the usual pile surfaces, as indicated in the drawings.

The gear 57 is in mesh with a gear 58 on the shaft 48 and also with an idler 59 mounted on the stud 60. This idler is in mesh with a gear 61 on the shaft 41—the shaft of the wheel 38. The gear 61 is in mesh 80 with a gear 62 on the shaft 47 of the wheel 44. The gear 61 is also in mesh with an idler 63 mounted on the stud 64, this idler being in mesh with a gear 65 on the shaft 40, this gear being in mesh with a gear 66 on the shaft 46. The gear 65 is also in mesh 85 with a gear 67 on an idler shaft 69, this shaft having eccentrically mounted thereon a pawl 70 which operates on a ratchet wheel 71 on the shaft 51 of the pick-up wheel 50, 90 so that this wheel is given an intermittent movement. The gear 67 is in mesh with an idler 72 mounted on a stud 73, this idler being in mesh with a gear 74 on the shaft 13 which is the shaft of the impression roll 11. 95 This idler 73 is also in mesh with an idler 75 mounted on a stud 76, this idler being in mesh with a gear 77 on the shaft 12 of the printing roll. This idler 75 has a broad face and also meshes with a gear 78 on the 100 shaft 28, the wheels 78 and 77 being located in different vertical planes. The gear 78 meshes with a gear 79 on the shaft 22 which is the shaft of the ductor wheel 21. After leaving the bronzing wheel, the paper strip 105 may run over a guide wheel 80 mounted on a shaft 81, this shaft being provided with a gear 82 which is in mesh with the gear 58 before referred to.

It will be observed that the gearing is of 110 such a character that all the shafts run at the same surface speed. It will, however, be further observed that the diameter of the wheels 37, 38 and 39 and their companion wheels 43, 44 and 45 is greater than the 115 diameter of the printing wheel, which wheel is calculated to run, in the particular construction illustrated, at the speed given the strip by the tube forming devices. The traveling or surface speed of these wheels 37, 120 38, 39, 43, 44, 45 is therefore in excess of the speed of the strip, and, therefore, exercises a strain relieving function, as has been before indicated.

If it be desired to employ the various 125 wheels before referred to simply as a strain relieving device, the bronze box and ink fountains will be emptied, so that no printing or bronzing takes place.

Changes and variations may be made in 130

the construction by which the invention is carried into effect. The invention is not, therefore, to be limited to the specific construction hereinbefore described and illustrated.

What is claimed is:—

1. The combination with mechanism for forming a thin paper strip into a tube, of a source of supply from which the strip is continuously drawn, a traveling surface located and operating on the strip between the source of strip supply and the forming means, and means for driving the surface at a speed in excess of the speed of the strip.

15 2. The combination with mechanism for forming a thin paper strip into a tube, of a source of supply from which the strip is continuously drawn by the forming mechanism, a plurality of wheels located between the 20 source of supply and the forming means, and means for driving some of the wheels at a speed in excess of the speed of the strip.

25 3. The combination with mechanism for forming a thin paper strip into a tube, of a source of supply from which the strip is continuously drawn by the forming mechanism, a plurality of pairs of wheels between which the strip passes, said wheels being located between the source of supply and the forming 30 mechanism, and means for driving some of the pairs of wheels at a speed in excess of the speed of the strip.

35 4. The combination with mechanism for forming a thin paper strip into a tube, of a source of supply from which the strip is continuously drawn by the forming mechanism, a pair of printing wheels, and a revolving strain relieving mechanism between the printing wheels and the forming mechanism, 40 with which relieving mechanism the strip is

in contact, said relieving mechanism moving at a greater speed than the speed of the strip.

5. The combination with means for forming a thin paper strip into a tube, of a source of supply from which the strip is continuously 15 drawn by the forming means, a pair of printing wheels in the path of the strip, bronze applying means in the path of the strip, and means for driving the bronze applying means at a greater speed than the speed of the strip 50 whereby said bronze applying means also operates to relieve the strain on the strip.

6. The combination with means for forming a thin paper strip into a tube, of a source of supply from which the strip is continuously 55 drawn by the forming means, a pair of printing wheels in the path of the strip, a set of bronzing wheels in the path of the strip, and means for driving the bronzing wheels at a greater speed than the speed of the strip 60 whereby said bronzing wheels also operate to relieve strain on the strip.

7. The combination with means for forming a thin paper strip into a tube, said means including a pair of crimping wheels, of a 65 source of supply from which the strip is continuously drawn by the crimping wheels, a pair of printing wheels in the path of the strip, a set of bronzing wheels in the path of the strip, and means for driving the bronzing 70 wheels at a greater speed than the speed of the strip, whereby said bronzing wheels also operate to relieve strain on the strip.

In testimony whereof, I have hereunto set my hand, in the presence of two subscribing 75 witnesses.

SYDNEY I. PRESCOTT.
